UNITED STATES PATENT OFFICE

164,549

CATERPILLAR PULL TOY

Jesse F. Brice, East Aurora, N. Y., assignor to
Brice Toy & Novelty, Inc., East Aurora, N. Y.

Application April 21, 1951, Serial No. 14,911

Term of patent 3½ years

(Cl. D34—15)

To all whom it may concern:

Be it known that I, Jesse F. Brice, a citizen of the United States, residing at #522 Ridge Avenue, East Aurora, county of Erie and State of New York, have invented a new, original, and ornamental Design for a Caterpillar Pull Toy, of which the following is a specification, reference being had to the accompanying drawing, forming a part hereof, in which:

Fig. 1 is a side elevation of a caterpillar pull toy showing my new design.

Fig. 2 is a top plan view thereof.

Fig. 3 is a front elevation thereof.

Fig. 4 is a rear elevation thereof showing the parts in different positions than in Figs. 1-3.

I claim:

The ornamental design for a caterpillar pull toy, as shown.

JESSE F. BRICE.
